Primary Examiner — Khawaja Anwar*Assistant Examiner* — Taylor O Mortorff(74) *Attorney, Agent, or Firm* — Studebaker & Brackett PC(57) **CLAIM**

The ornamental design for a vacuum cleaner, as shown and described.

DESCRIPTION

FIG. 1 is a front, top and right-side perspective view of a vacuum cleaner showing our new design;

FIG. 2 is a rear, top and left-side perspective view thereof;

FIG. 3 is a front view thereof;

FIG. 4 is a rear view thereof;

FIG. 5 is a top view thereof;

FIG. 6 is a bottom view thereof;

FIG. 7 is a right-side view thereof, with the left-side view being a mirror image thereof; and,

FIG. 8 is a perspective view shown in a state of use.

The broken lines shown represent portions of the vacuum cleaner and form no part of the claimed design.

1 Claim, 8 Drawing Sheets(56)
